United States Patent Office.

THOMAS GOODRUM, OF PROVIDENCE, RHODE ISLAND.

Letters Patent No. 82,514, dated September 29, 1868; antedated September 16, 1868.

IMPROVEMENT IN CALIPERS.

The Schedule referred to in these Letters Patent and making part of the same.

TO ALL WHOM IT MAY CONCERN:

Be it known that I, THOMAS GOODRUM, of the city and county of Providence, in the State of Rhode Island, have invented a new and useful Improvement in Calipers; and I do hereby declare that the following is a full, clear, and exact description of the same, reference being had to the annexed drawings, making a part of this specification, in which—

Figure 1 is a perspective view of my invention as attached to a pair of calipers.

Figures 2 and 3 are detailed parts.

In the accompanying drawings, A, fig. 2, is a short rod or round piece of metal, at one end of which is a screw, the threads being made ratchet-shape. On the opposite end of A is fastened a suitable-shaped head, C, to be operated by the thumb and finger. On or near the centre of this rod is a swell or ball, made as a bearing in resisting end pressure. This swell or ball is fitted to a seat, as shown on fig. 3. This seat is made of suitable shape or form to allow A to vibrate when in operation as a ratchet, and also to rotate when operated as a screw. B, fig. 1, is a section of a circle, the under surface of which is concave, and provided with ratchet-teeth, cut diagonally, to fit screw on A.

To use my invention, A being fitted into its seat, and held there by head C, A is connected to B, so the ratchet-thread falls into and is held to the ratchet-teeth on B by a spring.

The advantages are the instantaneous change from one of its extreme capacities to the other, at the same time retaining all the qualities of nice adjustment, as, when the head, C, is pressed towards B, the ratchet-teeth are disconnected from screw on A, leaving the calipers free to open. When the pressure is removed, the ratchets again drop into their places. To close the calipers, they are merely pressed together, A operating upon B as a common pawl. When required to be nicely adjusted, the head, C, is rotated, turning the screw in ratchet-teeth on B, operating the calipers in the desired direction. This device is applicable to dividers, wrenches, &c.

I do not claim a pair of calipers as my invention; but

What I do claim, and desire to secure by Letters Patent of the United States, is—

The rod A, in connection with B, and as fitted to its seat, substantially as described, and for the purpose as set forth.
